(57) **CLAIM**

I claim the ornamental design for a glass and cooling or warming sphere, as shown.

DESCRIPTION

FIG. 1 is a front perspective view of a glass and cooling or warming sphere showing my new design;
FIG. 2 is a left side elevational view thereof;
FIG. 3 is a front elevational view thereof;
FIG. 4 is a right side elevational view thereof;
FIG. 5 is a rear elevational view thereof;
FIG. 6 is a top plan view thereof; and,
FIG. 7 is a bottom plan view thereof.

1 Claim, 4 Drawing Sheets
